UNITED STATES PATENT OFFICE.

LEO MULLEN AND JOSEPH JACKEVICH, OF COLLINGDALE, PENNSYLVANIA.

LIFE BELT.

Application filed February 7, 1927. Serial No. 186,438.

This invention relates to new and useful improvements in life belts, and has for its primary object to provide a device of this character consisting of a normally deflated 5 air bag constructed for attachment around the waist and having arranged therein a small compressed air container equipped with means for enabling the air to be discharged therefrom for filling the bag so 10 that the same will properly support a person within the water. A life belt of this character may be distributed amongst the passengers of a vessel, or as well may be secured around the waist of a bather so that 15 the bag may be charged with air in case of an emergency.

Our invention further aims to provide a life belt that may be readily rolled and disposed within a small container so that the 20 same may be conveniently carried in the pocket.

Yet another object is to provide a life belt of this character that is extremely simple of construction, inexpensive of manufacture 25 and one that is well adapted for life preserving purposes.

With the foregoing and other objects in view as the nature of the invention will be better understood, the same comprises the 30 novel form, combination and arrangement of parts hereinafter more fully described, shown in the accompanying drawing and claimed.

In the drawing wherein like reference 35 characters indicate corresponding parts throughout the several views:

Figure 1 is a fragmentary plan of a life belt constructed in accordance with the present invention.

Figure 2 is a fragmentary section disclosing more clearly the construction of the compressed air container.

Figure 3 is a section through a card board or metallic package within which the belt may be disposed when in a rolled condition, and

Figure 4 is an enlarged horizontal section taken substantially upon the line 4—4 of Figure 2 and looking downwardly in the 50 direction of the arrows for more clearly disclosing the inlet valve construction for the air container of the belt.

Now having particular reference to the drawing, our novel device consists of a 55 flexible non-elastic air receiving belt 5 of predetermined length and width, prefera-

bly of rubberized silk and having at its opposite ends, straps or other suitable means 6 whereby the belt may be secured around the waist of the wearer. 60

Arranged centrally within this belt 5 is a tubular air container 7 through a central threaded opening in the upper end of which is threaded an open ended sleeve 8, that extends through the top of the belt 5 as clearly disclosed in Figure 2, this sleeve being rigidly secured within the end of the container 7, and belt 5 by a suitable disc nut 9, while threaded upon the extreme end thereof is a closure cap 10. Rigidly mounted within the interior of this sleeve substantially intermediate the ends thereof is a spider 11 through the center of which loosely passes a pin 12 having a plate head 13 upon its lower end and upon the inner face of which is disposed a washer 14 for abutting the lower end of the sleeve to prevent the discharge of the air within the container through said sleeve. Surrounding the pin 12 between the washer 13 and spider 11 is 75 a retractile coil spring 15 secured at its ends to the spider and to the pin for normally drawing the pin upwardly through the sleeve so that the washer 13 will firmly engage the lower end of the sleeve for a purpose just described. 80

Rigidly arranged upon the lower end of the container 7 is a cap 16 formed to provide a central socket 17 that engages within the container as clearly disclosed in Figure 2. The back wall of this socket is formed with air outlet openings 18, while slidably arranged through a central opening in said back wall is a valve pin 19 upon the inner end of which is a plate head 20 upon the inner face of which is a washer 21 for disposition over the openings for preventing the escapage of the air from the container into the belt. The outer end of the pin 19 is equipped with a thumb button 22, while surrounding the pin between the button and back wall of the socket 17 is an expansible coil spring 23 for normally forcing the pin downwardly so as to tightly maintain the openings 18 closed. 95 100 105

Obviously however, when the belt is arranged around the waist of the wearer it will only be necessary to press the finger against the belt 5 directly beneath the button 22 so that the button may be raised for uncovering the openings 18 whereupon the air will escape from the container into the 110

belt 5 for completely charging the same with the compressed air that has been previously injected into the container through the valve at the upper end thereof.

5 If desired, the belt may be rolled as indicated in Figure 3 and disposed within a suitable card board or metal package 24 so that the same may be conveniently carried in the pocket.

10 It will therefore be seen that we have provided a highly novel, simple and inexpensive life belt that is well adapted for all the purposes heretofore designated and even though we have herein shown and described 15 the invention as consisting of certain detail structural elements, it is nevertheless to be understood that some changes may be made therein without affecting the spirit and scope of the appended claim.

20 Having thus described the invention, what we claim is:—

In a life belt of the character described, a flexible non-elastic air bag of predetermined diameter, means at the opposite ends 25 of the bag for permitting of the securing of the same around the waist of a wearer, a

compressed air tank arranged within the bag, means in the upper end of the container extending through the upper edge of the bag for normally closing the interior of the container to the atmosphere but to permit the injection of compressed air into the container, an inwardly directed socket within the lower end of the container having air escape openings in its inner end, a 35 valve stem slidably disposed within a central opening in the inner wall of said socket, a head upon the inner end of the pin, a washer upon the inner face of the head for engagement over the air discharge openings, 40 a finger button upon the outer end of the pin whereby the head may be forced inwardly of the openings to permit the passage of the air therethrough into the bag and an expandible coil spring surrounding the pin between the head and the inner wall of said socket for normally maintaining the valve closed.

In testimony whereof we affix our signatures.

LEO MULLEN.
JOSEPH JACKEVICH.
